CLAIM

The ornamental design for an orthopedic cane shaft, substantially as shown and described.

DESCRIPTION

FIG. 1 is an elevated front perspective view of an embodiment of an orthopedic cane shaft in accordance with the present invention.

FIG. 2 is a side elevation view of the embodiment of the orthopedic cane shaft of FIG. 1.

FIG. 3 is an alternate side elevation view of the embodiment of the orthopedic cane shaft of FIG. 1.

FIG. 4 is a rear elevation view of the embodiment of the orthopedic cane shaft of FIG. 1.

FIG. 5 is a front elevation view of the embodiment of the orthopedic cane shaft of FIG. 1.

FIG. 6 is a top view of the embodiment of the orthopedic cane shaft of FIG. 1.

FIG. 7 is a bottom view of the embodiment of the orthopedic cane shaft of FIG. 1; and,

FIG. 8 is a cross-sectional side view of the embodiment of the orthopedic cane shaft of FIG. 1 taken along line 8-8 shown in FIG. 5 looking in the direction of the arrows.

The broken lines illustrate environmental subject matter and form no part of the claimed design.

1 Claim, 5 Drawing Sheets
